UNITED STATES PATENT OFFICE.

HUGO HAISS, OF PITTSBURG, PENNSYLVANIA.

UNIVERSAL BEAM-FRAME.

No. 866,460.

Specification of Letters Patent.

Patented Sept. 17, 1907.

Application filed April 20, 1907. Serial No. 369,257.

To all whom it may concern:

Be it known that I, HUGO HAISS, a subject of the Emperor of Germany, residing at Pittsburg, in the county of Allegheny and State of Pennsylvania, have 5 invented certain new and useful Improvements in Universal Beam-Frames, of which the following is a specification, reference being had therein to the accompanying drawing.

This invention relates to universal beam frames, and 10 the invention has for its object to provide a novel skeleton frame for concrete beams and girders to add rigidity to them as well as to prevent sagging and cracking thereof.

My invention aims to provide a metallic frame adapted 15 to be embedded in concrete beams or girders, the frames being constructed to equally distribute in the beam the stresses and strains exerted thereon, thus preventing shear stresses at the edges of the supports. To this end, I have devised a metallic skeleton frame 20 wherein a series of bars or rods are arranged, locked together and anchored in a beam or girder. The series of bars can be arranged in sets or be duplicated according to the load of a beam or girder and as well as its span or stretch. In some instances, where the shear stresses 25 are excessive, I use stirrups and stirrup spacing bars in connection with the beam frame, the stirrups being assembled in closer proximity to one another at the ends of the beam, thereby preventing dislocation of the beam or girder due to shear stresses. As a reinforcement 30 for beams and girders, the universal frame provides an anchorage to prevent slipping of the bars embedded in the concrete, the reinforcement sustaining the entire weight of the beam or girder, thus providing a beam or girder of considerable strength and rigidity and free 35 from all danger of being dislocated by vibratory or constant load stresses.

The detail construction entering into my invention will be hereinafter more fully described and then specifically pointed out in the appended claims.

40 Referring to the drawing forming part of this specification, like numerals of reference designate corresponding parts throughout the several views, in which:—

Figure 1 is a perspective view of one end of a beam frame or metallic reinforcement constructed in accordance 45 with my invention, with stirrups as attached to the same, Fig. 2 is a plan of a clip used for securing the stirrups to the stirrup spacing bars, Fig. 3 is a perspective view of the stirrups removed from a frame, the stirrups in this instance being constructed of round bars, Fig. 4 is a similar view illustrating the stirrups 50 formed from hoop-iron, Fig. 5 is a plan of a clip used in connection with the form of stirrups shown in Fig. 4, Fig. 6 is a perspective view of a beam frame, illustrating a simplified form consisting of a single layer of bars 55 or rods, Fig. 7 is a perspective view of one end of a frame constructed with a double layer of bars or rods,

Fig. 8 is an end view of the frame lock used in connection with the frame illustrated in Fig. 6 of the drawings, Fig. 9 is a similar view of a frame lock used in connection with the frame illustrated in Fig. 7, Fig. 10 60 is a front elevation of a double frame lock embedded in a beam or girder, Fig. 11 is an inverted plan of the same without the embedding concrete. Fig. 12 is a side elevation, Fig. 13 is a perspective view of the double frame lock, Fig. 14 is a plan of a frame lock 65 illustrating twisted bars secured therein, Fig. 15 is an elevation of the same embedded in a concrete beam or girder, Fig. 16 is a side elevation of the same.

To put my invention into practice, I construct my improved beam or girder frame of a plurality of parallel rods or bars 1 arranged in a horizontal plane and maintained in this position parallel with one another by single frame locks 2 and 3, said locks comprising bars through which the rods or bars 1 extend. The frame locks 2 and 3 are provided with depending supporting 70 plugs 4 and with laterally projecting separating plugs 5. The frame locks 2 constitute what I will hereinafter term as the end housings of a beam frame, while the locks 3 constitute intermediate housings, which are preferably located in close proximity to the end housings 75 on account of the ends of the concrete beam or girder being subjected to shearing stresses. It will therefore be observed that considerable space may exist between the intermediate housings at one end of a beam and the intermediate housings at the opposite end, the amount of space entirely depending upon the length and span of the beam. The locks 2 and 3 and the rods or bars 1 form practically the foundation 80 of a concrete beam or girder, and in order that the ends of the rods or bars 1 can be firmly anchored in 85 the plastic composition of the beam or girder, I provide the ends of the bars or rods 1 with heads 16, which will also prevent slipping of said bars in the concrete.

Upon the locks 3 of the intermediate housings are 90 secured by bolts and nuts 7, locks 8 and 9, the lock 8 housing rods or bars 10, while the lock 9 houses the rods or bars 10 and rods or bars 11, thus forming two layers of rods or bars between the intermediate housings.

100 For supporting the ends of the rods or bars 10 and 11, I provide the locks 2 of the end housings with rectangular shaped brackets 12, upon which are fastened by nuts and bolts 14, locks 15, said locks receiving the upwardly bent ends of the rods and bars 10 and 11, the ends after passing through the locks 15 being parallel with the rods or bars 1 and provided with heads 16. In elevating and anchoring the ends of the rods or bars 10 and 11 in the manner just described, there is less liability of the central portion of the beam 110 frame sagging or deflecting than would be the case if the ends of the rods or bars 10 and 11 remain parallel.

with the rods or bars 1. I also reduce the percentage of elongation (within an elastic limit) of the rods or bars 1.

The beam frame just described constitutes a frame consisting of end housings and intermediate housings 5 having a double layer of rods and bars, and reference will now be had to Figs. 6 and 8 of the drawings, wherein I have illustrated a simplified form of frame having a single layer of bars or rods. The locks 2 and 3 of the end and intermediate housings carry rods or bars 16' 10 and 17, the ends of the rods or bars 17 being bent upwardly and housed in elevated locks 18 carried by angular brackets 19, secured upon the locks 2 of the end housings. This construction of frame is for beams and girders of less dimensions and loads than those in 15 connection with which the double layer of rods and bars is used.

In Figs. 14 to 16 inclusive, I have illustrated a single lock 20 having supporting plugs 4 and separating plugs 5, the locks 20 having twisted or irregular shaped 20 rods or bars 21. When the locks are cast upon the rods or bars 21, I retain the rods or bars in position by wire 22 embracing said rods or bars, said pieces of wire being embedded in the cast lock to prevent dislocations and breaking of locks.

25 Reference will now be had to Figs. 1 to 5 inclusive wherein I have illustrated my improved beam frame as provided with stirrups for producing a more rigid construction, where the shearing stresses of beams or girders are considerable. The stirrups and their fastening means practically constitute an attachment for my improved frames, and as such, reference will be had to Fig. 1, where I have illustrated the stirrups in connection with a frame having a double layer of rods or bars. One of the intermediate housings at each 30 end of the frame is provided with a rectangular support 23, and secured to said supports and to the brackets of the end housings are parallel spacing bars 24. Secured to said bars by clips 25 are rectangular stirrups 26 having overlapping ends 27. The stirrups 26 are closely arranged adjacent to the intermediate and 35 end housings. The stirrups illustrated in Figs. 1, 2 and 3 of the drawings, are constructed of round rods, while the stirrups illustrated in Figs. 4 and 5 are constructed of hoop-iron, each stirrup having its ends 40 fastened, as at 28.

It will be apparent from the illustration of my invention, that I have devised positive and reliable means for reinforcing a beam or girder formed of plastic material, the reinforcement extending from one end 50 of a beam or girder to the other and providing a continuous reinforcement having a low percentage of elongation and a high tensile strength. A beam or girder construction reinforced by my improved frame is capable of safely withstanding a concentrated or 55 moving load without cracking, shearing or in any manner dislocating parts of the beam or girder.

I desire it to be understood that the principle of my improved beam and girder frame can be readily embodied in beam and girder construction, especially 60 where floors are to be supported over large spans, as bridge floors, ware houses, factory buildings, etc.

What I claim and desire to secure by Letters Patent, is:—

1. A beam frame for reinforcing concrete construction, 65 consisting of two layers of parallel rods or bars, intermediate housings holding said rods or bars in position,

end housings embracing the ends of the lowermost layer of rods or bars and supporting in an elevated position the bent ends of the uppermost layer of rods or bars, heads carried by the ends of said rods or bars, plugs carried by 70 said housings, space bars supported by said housings, stirrups carried by said space bars, and embracing said rods or bars.

2. A beam frame for reinforcing concrete construction, consisting of two layers of parallel rods or bars, intermediate housings locking said rods and bars together, end housings carried by the ends of the lowermost layer of rods or bars and supporting the bent ends of the uppermost layer of rods or bars, heads carried by the ends of said rods or bars, spacing bars carried by said housings, 80 and stirrups secured to said bars and embracing said rods intermediate said end housings.

3. A beam frame for reinforcing concrete construction, consisting of two layers of parallel rods or bars, intermediate housings holding said rods or bars parallel, 85 end housings embracing the ends of the rods or bars of the lowermost layer and for supporting the bent ends of the rods or bars of the uppermost layer, said rods or bars having anchor ends, space bars carried by said housings, and stirrups supported by said bars and embracing said rods or bars.

4. A beam frame for reinforcing concrete construction, consisting of horizontal layers of parallel rods or bars, intermediate housings embracing said rods or bars, end housings embracing the rods or bars of the lowermost 95 layer and for supporting the bent ends of the rods or bars of the uppermost layer, space bars supported by said housings, and stirrups carried by said space bars and surrounding said rods or bars.

5. A beam frame for reinforcing concrete construction, 100 consisting of two horizontal layers of parallel rods or bars, intermediate housings holding said rods or bars in position, end housings embracing the rods or bars of the lower layer, and supporting the ends of the upper layer of rods or bars, the ends of said rods or bars being bent upwardly at an angle to the rods or bars of the lower layer, stirrups surrounding said rods or bars and arranged in close order to the end housings, and means carried by said housings for supporting said stirrups.

6. A beam frame for reinforcing concrete construction, 110 consisting of two layers of parallel rods or bars, housings embracing the rods or bars of both layers, housings embracing the rods or bars of the lower layer and some of the rods or bars of the upper layer, housings embracing the ends of the rods or bars of both layers and supporting 115 the bent ends of the rods or bars of the upper layer in an elevated position with relation to the lower layer, space bars carried by said housings, stirrups connected to said bars and arranged in close order with relation to said housings.

7. A beam frame for reinforcing concrete construction, 120 consisting of two layers of parallel rods or bars, housings embracing the rods or bars of both layers, housings embracing the rods or bars of the lower layer and some of the rods or bars of the upper layer, housings embracing the ends of the rods or bars of both layers and supporting 125 the bent ends of the rods or bars of the upper layer in an elevated position with relation to the lower layer, stirrups embracing said rods or bars, and means carried by said housings for supporting and spacing said stirrups.

8. A beam frame for reinforcing concrete construction, 130 consisting of two layers of parallel rods or bars, housings embracing the rods or bars of both layers, housings embracing the rods or bars of the lower layer and some of the rods or bars of the upper layer, housings embracing the ends of the rods or bars of both layers, and supporting 135 the bent ends of the rods or bars of the upper layer in an elevated position with relation to the lower layer, and stirrups embracing said rods or bars.

9. A beam frame for reinforcing concrete construction, 140 consisting of two superposed layers of rods or bars, the ends of the rods of the upper layer of rods being bent upwardly, superposed housings each embracing the rods or bars of a layer, housings embracing the rods or bars of the lower layer and some of the rods or bars of the upper layer, housings embracing the ends of the rods or bars of 145

- both layers and supporting the bent ends of the rods or bars of the upper layer in an elevated position with relation to the lower layer, and spacing and supporting plugs carried by certain of said housings.
- 5 10. A beam frame for reinforcing concrete construction, consisting of two superposed layers of parallel rods or bars, transversely-extending housings each embracing all of the rods or bars of both layers, transversely-extending housings each embracing all of the rods or bars of the lower layer and some of the rods or bars of the upper layer, the rods of the upper layer having the ends thereof bent in an angular manner with respect to the remaining portions of the rods, transversely-extending housings embracing the ends of the rods or bars of both layers and supporting the angular ends of the rods or bars of the upper layer in an elevated position with relation to the lower layer, said rods or bars having anchor ends.
- 10 11. A beam frame for reinforcing concrete construction, consisting of two superposed layers of parallel rods or bars, transversely-extending housings each embracing all of the rods or bars of both layers, transversely-extending housings each embracing all of the rods or bars of the lower layer and some of the rods or bars of the upper layer, the end portions of the rods of the upper layer bent in an angular manner with respect to the remaining portion of said rods, housings embracing the ends of the rods or bars of both layers and supporting the angular ends of the rods or bars of the upper layer in an elevated position with relation to the lower layer.
- 15 12. A beam frame for reinforcing concrete construction, comprising two superposed layers of longitudinally-extending rods, the rods of each layer being arranged in transverse alignment with respect to each other, the ends of the rods of the upper layer being bent upwardly and then horizontally so as to extend in a plane above the plane of the end of the rods of the lower layer, transversely-extending superposed housings each embracing the rods of a layer, transversely-extending housings embracing the ends of the rods of both layers and supporting the bent ends of the rods of the upper layer in an elevated position with respect to the ends of the rods of the lower layer.
- 20 13. A beam frame for reinforcing concrete construction, comprising two superposed layers of longitudinally-extending rods, the rods of each layer being arranged in transverse alignment with respect to each other, the ends of the rods of the upper layer being bent upwardly and then horizontally so as to extend in a plane above the plane of the end of the rods of the lower layer, transversely-extending superposed housings each embracing the rods of a layer, transversely-extending housings embracing the ends of the rods of both layers and supporting the bent ends of the rods of the upper layer in an elevated position with respect to the ends of the rods of the lower layer.
- 25 14. A beam frame for reinforcing concrete construction, comprising two superposed layers of longitudinally-extending rods, the rods of each layer being arranged in transverse alignment with respect to each other, the ends of the rods of the upper layer being bent upwardly and then horizontally so as to extend in a plane above the plane of the end of the rods of the lower layer, transversely-extending superposed housings each embracing the rods of a layer, transversely-extending housings embracing the ends of the rods of both layers and supporting the bent ends of the rods of the upper layer in an elevated position with respect to the ends of the rods of the lower layer, the ends of the rods of each layer being enlarged to constitute anchors.
- 30 15. A metallic reinforcement for concrete construction embodying a frame comprising a series of longitudinally-extending rods arranged in parallelism with respect to each other, the intermediate rods of said series having the ends extending upwardly at an angle and then in a longitudinal direction, transversely-extending housings embracing all of said rods, transversely-extending housings embracing the upper rods of said series at the ends thereof, and transversely-extending housings supported from the last-mentioned housings and embracing the ends of the intermediate rods.
- 35 16. A metallic reinforcement for concrete construction embodying a frame comprising a series of longitudinally-extending rods arranged in parallelism with respect to each other, the intermediate rods of said series having the ends extending upwardly at an angle and then in a longitudinal direction, transversely-extending housings embracing all of said rods, transversely-extending housings embracing the upper rods of said series at the ends thereof, and transversely-extending housings supported from the last-mentioned housings and embracing the ends of the intermediate rods, each of said rods having the ends thereof enlarged to constitute an anchoring beam.
- 40 In testimony whereof I affix my signature in the presence of two witnesses.
